FOUNDATION DEVICE FOR LOAD
SUPPORTING COLUMNS

Richard J. Neutra, Los Angeles, Calif.

Application August 4, 1945, Serial No. 608,938

8 Claims. (Cl. 189—42)

1

This invention relates to foundations for load-supporting columns as used in the erection of houses, walls and other building structures for supporting ceilings, roofs or other superimposed loads.

It has been common practice heretofore to construct such foundations of a block of brick, stone or concrete emplaced within an excavation in the ground and embedding or anchoring the lower portion of the column in or to the block, the block serving to transmit the vertical load to the ground and acting in the manner of a cantilever under the stress of lateral forces.

Such a foundation is not entirely satisfactory inasmuch as its resistance to forces in different directions can be computed only approximately before erection so that as a matter of safety the foundation is often considerably over-dimensioned. Another disadvantage of such a foundation is that it is unsuitable for use for the erection of buildings composed of so-called prefabricated elements which must be put together on the building site in a speedy and efficient manner. Up to this time proposals for the erection of prefabricated or shop-fabricated buildings have called for foundations for the supports and columns the same as are required for ordinary buildings. This means that all of the elements of the building, such as the wall, ceiling, roof and other elements, are subject to prefabrication leaving only the execution of the usual foundation work and the anchoring of the superstructure thereto to be done later. This foundation work takes considerable time so that the erection of the building is unduly prolonged.

One object of the present invention is to provide a foundation for load supporting columns for buildings of any kind, which foundation consists only of comparatively light structural elements arranged in such a rational interconnection and well controllable interplay that an exact advance computation of the dimensions of the members of the foundation is feasible in view of stresses in all directions, provided their magnitude can be foreseen.

Another object of the invention is to provide a foundation device for load supporting columns for buildings of any kind, which foundation in principle avoids the use of a heavy inert block built of stone, brick or concrete, in order to make prefabrication, and transport from shop to distant premises, of all of the elements of the foundation and of the foundation as a whole reasonable, feasible, economical and practical.

Another object of the invention is to provide 55 of the foundation device;

2

a foundation device for load supporting columns for buildings of any kind in which the jamming devices for the fixation of the column into the foundation structure are shaped and arranged in such a manner that their jamming effect is increased by every push or shock which tends to move the column between these jamming means, so that the fixation of the column remains essentially unweakened and unchanged.

10 Another object of the invention is to provide a foundation device for load supporting columns for buildings of all kinds, which foundation itself can be supported by the surface of the ground so that any and all excavation can be spared, provided 15 the base member of the foundation device is large and strong enough to secure the required stability and load transmission to the soil. But even if it should prove desirable for special reasons to arrange the foundation on a lower level which 20 calls for a certain excavation, this excavation does not need any exactness and no larger dimensions of its depth and width than are necessary to give space for the members of the foundation extending below the surface of the ground. In any case, 25 to produce an excavation of this character will take less time and is considerably less expensive than an excavation for the usual foundation.

A foundation device, according to the present invention, consists principally of a base-member, 30 executed as a rule in the shape of a rigid plate, with or without interruptions (holes), or in the shape of a ring; further, of a shoe for supporting the lower end of the column; one or a plurality of structures surrounding the column, to be fixed 35 and borne by the said base-member, and on their part supporting directly or indirectly the bearings of jamming-members, arranged around the columns and pressed against it on a level high enough above the said shoe. The said jamming 40 members are shaped and arranged in such a way that the jamming effect is automatically increased whenever any force tends to move the column out of its normal position between these jamming members. A simple means to accomplish 45 this action is to construct the jamming members in the shape of cams.

In the accompanying drawing:

Figure 1 is a vertical cross-sectional view of a foundation device embodying a preferred form 50 of the invention;

Figure 2 is a fragmentary plan view of the foundation device in part sectional, taken on the line 2—2 of Fig. 1;

Figure 3 is a detail view of a shoe forming part

Figure 4 is a vertical cross-sectional view of a modified form of the foundation device;

Figure 5 is a fragmentary plan view of the form of foundation device shown in Fig. 4;

Figure 6 is a vertical cross-sectional view of still another form of the foundation device;

Figure 7 is a fragmentary plan view of the form of foundation device shown in Fig. 6;

Figure 8 is a vertical cross-sectional view of a one-story house, viewed endwise, showing the manner in which the foundation devices (specifically the foundation devices of Figs. 4, 5, and 6, 7) are adapted to support the vertical columns thereof;

Figure 9 is a vertical cross-sectional view of the house of Fig. 8, viewed sidewise.

In the mode of execution of the foundation device as indicated in Figures 1 and 2, there is provided a base plate 1 placed upon the surface of the ground. It is sufficiently large and rigid to secure stability of the foundation. In order to render this plate rigid, it is provided with ribs; i. e., in an arrangement as shown consisting of a circular rib 2 and radial ribs 3 proceeding from the circular rib 2 toward the periphery of the base plate 1. In order to prevent any lateral movement of the base plate 1, it is provided with a rim 4 projecting downward at the periphery, and shaped like a knife in order to facilitate the driving of this rim into the soil when the base plate 1 is placed upon the ground.

In the center of the base plate 1 a shoe 5 is arranged, provided with a flange 6 containing four oblong holes 7 (see the plan view of the shoe represented by Figure 3). This shoe 5 is fastened to the base plate 1 by means of four screws 8 projecting through the oblong holes 7 upward, the oblong shape of these holes permitting adjustments of the shoe on the base plate, within certain limits, in every direction.

On a certain level above the base plate 1 a ring-shaped table 9 is arranged upon a plurality of supports 10 which are carried by and fastened to the base plate 1. Each of these supports 10 consists of a plurality of braces arranged in such a way that a perfect stability of the position of the ring-shaped table 9 is secured. On four points of the top of the ring-shaped table 9, bearings 11 are placed, each of which carries a jamming cam 12. The bearings 11 with the cams 12 are arranged in such a manner that two pairs of cams 12 are formed. The individual cams of each pair are diametrically opposed to each other and are working as jamming members when pressed against the column 13 which in its vertical position between these cams 12 is supported at its lower end by the shoe 5. Each bearing 11 is provided with a downward projecting portion 14 protruding from the base plate 15 of the bearing into a slot-shaped and radially arranged space 16 of the table 9 in which the projection 14 is guided. In the space 16 a screw 17 is supported in a radial position relative to the ring-shaped table 9, this screw having on its inner end a head 18 engaging the inner wall of the ring-shaped table 9, and on its outer end a hexagonal portion 19 with which, by means of a wrench, the screw 17 can be turned. The projecting portion 14 of the bearing 11 contains a hole provided with female thread fitting to the thread of the screw 17 which penetrates this hole so that the bearing is moved radially in the one or the other direction if the screw 17 is turned in the one or the other direction. In this way the bearings 11 can be moved toward

the column 13 and the cams 12 pressed vigorously against the column.

Every cam 12 is supported by the two parts of its bearing 11 by means of the pivots 20, 21. The pivot 21 is longer than the pivot 20, so as to project from the bearing in which it lies and contains on its end portion a screw thread 22. A washer 23 and a nut 24 are put onto the said screw-shaped end 22 of the pivot 21 and by screwing tightly the nut 24 on the screw 22, the washer 23 is pressed against the bearing 11 and acts like a brake on the cam 12 so that the cam can be fixed by the friction produced by the washer in any position. The cam can again be rocked around its pivot when the friction is released by slightly unscrewing the nut 24.

A column 13 to be fixed by means of a foundation as described is brought into a vertical position with its lower portion between the four cams 12, which in a preliminary phase are withdrawn from the center far enough to permit the column moving downward without being jammed. In this manner the bottom end of the column can be inserted into the shoe 5. The cams 12 are fixed at their bearings 11 by means of the braking washers 23, so that their smallest radius is in a position perpendicular to the side surface of the column 13; the position of the smallest radius of the cams can be marked by a line 25. The column, supported at its bottom by the shoe 5, is to be held in an approximately vertical position and the four cams 12 are moved by means of the screws 17 toward the column 13 and pressed to it. At first this pressure is exerted only to such a degree that the column is held in a supposed vertical position by means of the cams 12 and the shoe 5. This accomplished, it has to be checked whether the column is exactly vertical or only approximately so; in this latter case, the exactly vertical position can be achieved by loosening all of the nuts of the screws 8 by which the shoe 5 is fixed to the base member 1, so that the shoe 5, due to the oblong shape of the screw holes 7, can be moved upon the base member 1 in every horizontal direction within certain limits. By this means, the shoe can be put into the position in which the column held by the four cams at a level above the shoe 5, is exactly vertical. Then the nuts of the screws 8 are tightened and the four cams pressed against the column as tightly as possible. Should, in this stage of fixing the column, the one or the other of the cams not touch the column at the point of its shortest radius (which can be seen by observing the marker 25), the particular cam is to be withdrawn just sufficiently to allow the proper adjustment. For this purpose, the nuts 24 of the cams in need of adjustment are loosened somewhat so that the braking action of the washers 23 is diminished and turning of the cams becomes possible. After the cams are adjusted, the nuts 24 are again tightened in order to hold the cams in the adjusted position until their pressure toward the column can again be greatly increased. This done, all of the nuts 24 are once more loosened so that the cams can turn around their pivots 20, 21 in case they are caused to roll upon the surface of the column.

If, for example, a vertical shock upward occurs in consequence of an earthquake, the column may tend to move upward in between the four cams. This would have the consequence that the cams begin to roll upon the surface of the column while turning upward around their pivots 20, 21. However, immediately when such a rolling movement

of the cams is initiated, a new point of the peripheral arc of the cam comes in touch with the column. This new point of contact is further from the pivotal center than the length of the shortest radius which in the original position of the cam and before the beginning of this rolling movement was perpendicular to the column. The consequence thereof is that the jamming power of the cam increases at once and at the very beginning of such a rolling movement and thus the upward tendency or relative movement between the base and is stopped before it really can proceed to any substantial extent. A downward movement of the column is hardly possible at all; but even the slightest downward tendency would be prevented in the same manner by the working of the cams as above described for an upward movement of the column. Also every other cause for loosening or for shifting or displacing of the column by lateral forces (wind pressure, etc.) is rendered harmless, because the said jamming action of the cams which automatically increases with every incipient move of the column between the cams, inhibits every movement from the very beginning.

The Figures 4 and 5 show in elevation and plan view another mode of execution of a foundation device according to the invention. This mode of execution differs from the first one in essence by the fact that the cams forming the jamming device are carried by levers connected at their outside ends to supports fixed to the base member and are affected by the weight and the load of the column in such a manner that they are held in closest touch with the surface of the column.

Upon the base member 28 are fixed four supports 27, each of which consists of a horizontal plate 28 and props 29 and 30 arranged in such a manner that the shape and the position of these supports are stably resistant to all strains which possibly may occur. On the plate 28 of each of the supports 27 a bearing 31 consisting of two pivots 32, 33 of an eccentric 34 are carried. The ring 35 surrounding the eccentric 34 is fixed to the outer end of a lever 36 arranged in a radial plane, the inner end of which lever is provided with the bearings for the two pivots 37, 38 of a cam 39. Closely adjacent to the bearings for the cam 39, the lever 36 contains a hole 40 extending from the top to the bottom, this hole being penetrated by a bar 41, the lower end of which is connected to eyes 42 of a shoe 43. This said shoe serves to support the bottom of the column 44 to be fixed and to be held in an upright position by being jammed between a plurality of cams 39, situated on a level above the shoe 43. The upper end portion of the bar 41 is provided with a screw thread and, as mentioned, penetrates the hole 49 of the lever 36. The upper opening of the hole 40 is surrounded by a concavity in the shape of a spherical segment in which is fitted a washer 45. The bottom of this washer is shaped as a convex spherical segment fitting into the concavity of the lever 36. A nut 46 gives the upper end portion of the bar 41 a support, the bottom of the nut 46 lying on the washer 45 which is capable of adjustment by movement within the concavity; the hole 40 is wide enough to allow, within certain limits, different positions of the bar 41.

The weight of the column 44 and the load supported by the column are transmitted to the shoe 43 and press it downward. Thus the bars

41 which are connected to the shoe 43 are pulled downward and act upon the levers 36 in such a manner that these levers are caused to turn with their inner ends downward around the eccentrics 34 which serve as pivots for the levers 36, the rings 35 surrounding the eccentrics 34 forming a part of the levers. The consequence is that the cams 39 are pressed against the column and exert a jamming effect on it. The greater the load supported by the column, the greater also the pressure of the cams 39 onto the column and hence the jamming action holding the column fixed in its vertical position.

Obviously for this action, it is necessary that the final position of the levers 36 be, as shown in Figure 4, sloping up from the eccentrics 34, as a pivot for the said levers, to the inner ending of the levers which carry the jamming cams 39. In order to make required adjustments of the position of the levers possible, the eccentrics 34 of each lever 36 can be turned around its pivots 32, 33 which lie in the bearing 31. Thereby, the center of the eccentric ring 35 is displaced in the one or the other direction, which means that the distance between the center of the turning motion of the lever 36 and the column is increased or decreased, according to the displacement of the eccentric 34. In this manner, it is possible to obtain the most favorable angle of levers 36 in relation to the horizontal plane.

The turning of the eccentric 34 is effected by means of a screw 47, carried by secondary bearings 48 of the bearing 31, and a toothed wheel 49 fixed to one of the pivots 33 of the eccentric 34. This toothed wheel fits to the screw 47 which can be turned by means of a hand wheel 50, and which, in turn, drives the toothed wheel 49. By this means, the eccentric 34 can be moved in the one or the other direction according to the direction in which the screw 47 is turned. The lever 36 to which the ring 35 of the eccentric 34 is fixed, can be turned together with said ring 35 around the eccentric 34, the revolving center being the center of the eccentrically pivoted circular disc 34. If this disc (eccentric) 34 revolves around its pivots 32, 33, the center of the circular disc 34 is displaced and hence the distance between this center of the disc 34 and the surface of the column 44 is changed. It is decreased or increased according to the direction in which the eccentric disc 34 with its ring 35 moves outward or inward as caused by the turning of the hand wheel 50 in the one or the other direction. By this shift of the eccentric and its ring, the inclination of the lever 36 and the pressure exerted by the jamming cams 39 against the column 44 can be varied. In order to make it possible to accommodate the foundation to columns of different sizes of cross-section, in case the adjustment by turning the eccentric disc 34 around its pivots 32, 33, does not suffice, the bearing 31 which carries the eccentric 34 can, as a whole, be shifted upon the supporting plate 28 in the direction toward or from the column 44. For this purpose the bearing is fixed to the plate 28 by means of one or more screws 51, which, in the mode of execution as shown in Figures 4 and 5, are fastened to the base plate of the bearing 31, projecting downward, and penetrate a slot-shaped hole of the supporting plate 28, the long dimension of which hole extends radially relatively to the foundation device. In this manner the bearing 31 can be fixed on the plate 28 by tightening the nut 52 of the screw 51 in different positions to which it has been brought along the

slot-shaped hole, after loosening the nut 52. In order to diemburden the screw 51 of the radial force exerted on it by the reaction of the pressure of the cam 39 against the column 44, and by additional lateral forces due to wind pressure, etc., the surface of the supporting plate 28 is provided with ribs 53, in cross section like a saw blade, these ribs being arranged transversely to the radial direction in which the bearing 31 can be moved. The bottom surface of the base plate of the bearing 31 is also provided with such ribs which fit into the spaces between the ribs 53 of the supporting plate 28. The cooperation of these two interlocking rows of ribs after the nut 52 of the screw 51 is tightened, protects the screw 51 against the strains of shear caused by the reaction of the pressure of the cam 39 against the column 44. Thus the rough adjustment of the turning center of the lever 36 can be done by moving the bearing 31 toward or away from the column, and the fine adjustment by turning the eccentric 34 by means of the hand wheel 50, the screw 47 and the toothed wheel 49 in the one or the other direction.

Also, in the indicated mode of execution, the cam 39 can be locked in different positions to the lever 36 by means for example of a braking device. One of the pivots of the cam 39, here the pivot 38, is extended outward, the extension of this pivot being provided with a screw thread. On this extension is placed a washer 54 (see Figure 5) and a nut 55 by which the washer 54 can be pressed against that portion of the lever 36 which forms a bearing for the pivots of the cam 39. Thus the cam 39 can be locked in any position so that it is prevented from turning around its pivots.

For fixing a column 44 in the foundation described, the cams of the four levers 36 which are used if the column has a square cross section, are locked in their levers 36 approximately in a position in which they are supposed to finally remain while being pressed against the column. After that all of the levers 36 are turned upward around their eccentric 34, far enough to allow for the column 44 to be placed in between the cams 39, while the bottom of the column enters the shoe 43 and finds its support in it. Now the levers 36 are set free so that they can be drawn downward by the bars 41 under the weight of the column 44 which transmit the load to the shoe 43 and thus to the bars 41.

In consequence, the cams 39 are pressed against the column 44. Should it turn out that the cams 39 are in contact with the column at too high or too low a level, they can be brought to a more favorable level by turning the eccentric 34 in the one or the other direction. Should this mode of adjusting the turning center of levers 36 not suffice, the bearings 31 will have to be shifted on their supporting plates 28 as above described. Finally, the levers 36 are in order to adjust cams 39 in such a manner that they contact the column 44 with their smallest radius which is indicated by a mark on the cam 39. If now the levers 36 are set free, the column is correctly fixed by the cams 39. However, in any case, it will be necessary to check whether or not the column stands in an exactly vertical position. Whenever this is not the case, the vertical position can be accomplished either through adjusting the shoe 43 by screwing one or more of the bars 41 upward or downward, which is done by turning the nuts 46 or by adjusting one or more of the eccentric 34. As these adjustments 75

are necessary only to a very small degree, there is no danger that the different members of the construction will come too much out of symmetry. With sufficient experience, even exact symmetry can be obtained without difficulty.

As mentioned, the column 44 is held in position by the shoe 43 and between the cams 39 due to the weight of the column, the load acting on the shoe 43, which in turn acts on the levers 36 by means of the bars 41, thus pressing the cams 39 against the column 44. The larger the weight and the load of the column, the greater the pressure of the cams against the columns and the larger the jamming effect and the firmness of the fixation. Should there occur any tendency to move the column downwardly or upwardly between the cams 39 by wind pressure, earthquakes, etc., each of such a movement would tend to turn the cams 39 around their pivots 31, 38, and this again would tend to make the cams 39 contact the column along a longer radius than at the beginning of the movement.

The mode of execution shown in Figure 6 in elevation and in Figure 7 in a plan view, differs 25 from the mode of execution according to Figures 4 and 5 only insofar as the turning centers of the levers which carry the jamming cams are arranged in bearings, fastened directly upon the base-member of the foundation device so that 30 supports 27 as used in the preceding mode of execution, are eliminated. However, in this case, it is necessary to excavate the ground where the lower portion of the column projects downward. The column is supported by a shoe 35 arranged within this excavation. The base member of the foundation is ring-shaped in order to allow for the parts projecting downward into the excavation.

Levers 56 of the mode of execution shown in 40 Figures 6 and 7 correspond with levers 36 of the mode of execution, according to Figures 4 and 5; bars 57 correspond to bars 41; the shoe 58 corresponds to the shoe 43; the eccentric 59 corresponds to eccentric 34; the eccentric-rings 60 fixed to the levers 56 correspond to the eccentric-rings 35; the pivots 61, 62 of the eccentric 55 59 correspond to the pivots 32, 33 of the eccentric 34; the bearings 63 correspond to the bearings 31; the supporting plates 64 with their 50 ribs 65 correspond to the supporting plates 28 with their ribs 53; the cams 66 correspond to the cams 39; and so do the means for fixing the position of the cams 66 in relation to their levers 56, the means for adjusting the position of the cams 59 on their bearings 63, the means for adjusting the bars 57, the means for fastening the bearings 63 on the supporting plates 64 to the corresponding means of the mode of execution, according to Figures 4 and 5.

60 The difference between this form of foundation device and that of Figs. 4 and 5 consists only in the fact that the supporting plates for the bearings 63 are situated immediately upon the base-member 67 which itself lies directly upon the surface of the ground and is ring-shaped so as to give space for an excavation 68 in the ground in which the shoe 57 is situated, supporting there the bottom of the column 69. Thus the result of the structural differences between the two modes of execution of the foundation device is that the vertical distance between the surface of the ground and the upper limits of the members of the foundation is larger for the mode of execution according to Figures 4 and 5 than for the one according to Figures 6 and 7,

The choice of which of these two constructions should be used depends, therefore, upon the question at which level above grade the lowest floor of the building should be situated.

Figures 8 and 9 are vertical cross-sections of a one-story frame house, viewed lengthwise and sidewise respectively, and showing by way of example how the columns thereof are adapted to be supplied by the foundation devices hereinbefore described (which devices do not require blocks, bricks or concrete and no, or only limited, excavation) on unlevel terrain.

The foundation devices for the columns 44 and 69 of the house are drawn in a diagrammatical way, as an example on the right side, in accordance with the mode of execution shown in Figures 4 and 5 (without an excavation) and on the left side according to Figures 6 and 7 (with an excavation). Therefore the same parts of the foundation are designated in Figures 8 and 9 with the same numbers as in Figures 4 and 5, and in Figures 6 and 7, respectively.

For the rest, Figures 8 and 9 show that the columns 44 and 69 which are in this example of a building, arranged in two parallel rows give support to girders of the floor 71 and to the girders of the roof 72. They have, therefore, to bear the weight of the entire building and moreover they have to resist wind pressure and occasional stresses, especially earthquakes. Apart from all these loads and stresses the columns can serve to give support to the outside walls and to partition walls, as is usual, in the case of footings or foundations.

The foundations can be designed and dimensioned in such a manner that the columns 44 and 69 stand fixed and stable and can take over all of the stresses and loads as mentioned.

The modes of constructing the foundation devices hereinbefore described and illustrated are to be considered only as exemplary of the invention, and manifestly the invention may be embodied in other forms without departing from the spirit of my invention as defined by the following claims.

What I claim as my invention is:

1. A foundation device for load supporting columns for houses and buildings of any kind, comprising a base member intended to be placed upon the surface of the ground, a shoe for the bottom of a column intended to be fixed by the foundation in an upright position, a plurality of cams arranged around the space where a column is to be placed, so that they suitably fit to jam the column from different sides between one another at a level above the said shoe, eccentrically positioned pivots for the said jamming cams, a lever for each of the jamming cams, these levers being arranged around the space for the column in radial planes, the outer end of each of these levers being pivotally connected with the said base member, and the inner end of each of these levers containing the bearings for the pivots of the corresponding jamming cam, and bars, by means of which these levers are connected to the said shoe and which transmit the weight and load of the column, to be supported by the shoe, to the said levers, turning these levers downward in order to press the jamming cam toward the column when the column is positioned in said shoe.

2. A foundation device for load supporting

columns as set forth in claim 1, comprising for each of the jamming cams a device for fixing it in varied angular positions in relation to the said lever which contains the bearings for the pivots of

5 the jamming cam in order to fix the cam, before bringing it in contact with the column to be jammed, into a position in which it will contact the column at a point of its circumference pertaining to the smallest radius, said device after the column has been jammed, being capable of operation to set the cam free.

3. A foundation device for load supporting columns as set forth in claim 1, in which each of the eccentrically positioned pivots of the jamming

15 cams project outward from its bearing on the said lever and is provided with a screw thread, a washer-like braking disc sitting on the said thread projection of the said pivot, and a nut sitting likewise on the said projection of the

20 pivot and intended to fix the jamming cam in an angular position in relation to its bearings in which it contacts the column to be fixed at a point of its circumference pertaining to its smallest radius, whereupon the nut is to be loosened after the column has been fixed.

4. A foundation device for load supporting columns as set forth in claim 1, the said bars connecting the shoe with the levers carrying the jamming cams being adjustable in their effective lengths.

5. A foundation device for a load-supporting column for a building structure comprising a base member adapted to rest upon the ground, a shoe supported by the base member and providing a bearing surface for the lower end of a column, and a pair of jamming cams pivotally mounted on support members a substantial distance above the shoe and positioned in opposed relation for engaging the sides of said column.

40 6. A foundation device as set forth in claim 5 in which said jamming cams are adjustably mounted for bodily displacement toward and from each other.

7. A foundation device for a load-supporting 45 column comprising a base member adapted to rest upon the ground, a pair of levers each pivotally mounted at one end on said base member, jamming cams mounted upon the other ends of said levers and positioned in opposed relation 50 engaging the sides of said column, a shoe mounted at an elevation substantially below the cams for providing a bearing surface for the lower end of the column, and bars extending between said shoe and levers for transferring the load from 55 the shoe to said levers.

8. A foundation device as set forth in claim 7 including means for adjusting the pivotal mountings for said levers toward and from each other.

RICHARD J. NEUTRA.
